SPINNING DEVICE FOR DRILL PIPE

Win W. Paget, Mountain Brook, Ala., assignor to Joy Manufacturing Company, Pittsburgh, Pa., a corporation of Pennsylvania

Application May 5, 1955, Serial No. 506,148

20 Claims. (Cl. 81—53)

This invention relates to spinning devices and more particularly to spinning devices for rapidly rotating sections or stands of drill pipe during the coupling and uncoupling of the drill pipe joints of a drill string of an oil field rig.

In oil well drill rigs the drill pipe joints of the drill string are usually made and broken by make and break tongs, and during the coupling and uncoupling of the joints it is desirable to rotate rapidly the upper pipe section or sections to expedite the running in or going out of the drill string in the hole. The present invention is an improvement over the spinning device of my copending application Serial No. 335,477, filed February 6, 1953, now matured into Patent No. 2,746,329, dated May 22, 1956.

An object of the present invention is to provide an improved spinning device for drill pipe of a drill string such as used in oil well drilling. Another object is to provide an improved spinning device having improved and reliable means for engaging and rotating the drill pipe. A further object is to provide an improved spinning device having an endless chain for engaging and rotating the drill pipe and improved yieldable tensioning means for the endless chain. A still further object is to provide an improved spinning device having improved pipe-rotating means for engaging sections of drill pipe of different diameters. Yet another object is to provide an improved spinning device wherein the yieldable pipe-engaging means is associated with the means for engaging pipe sections of different sizes. Still another object is to provide an improved spinning device which is hydraulically positioned, hydraulically engaged with a drill pipe, and hydraulically driven. A still further object is to provide an improved spinning device which has self-centering means for centering the same with respect to the drill pipe. These and other objects and advantages of the invention will, however, hereinafter more fully appear in the course of the ensuing description.

In the accompanying drawings there is shown for purposes of illustration one form which the invention may assume in practice.

In these drawings:

Fig. 1 is a plan view illustrating a preferred embodiment of the spinning device with a portion of its associated supporting structure shown in horizontal section.

Fig. 2 is an enlarged horizontal sectional view of the spinning device shown in Fig. 1, with its supporting portion broken away and with the pipe-engaging and rotating chain in operative position with respect to the drill pipe section.

Fig. 3 is a view, similar to Fig. 2, showing the pipe-engaging and rotating chain in its released inoperative position.

Fig. 4 is a vertical section taken in the planes of line 4—4 of Fig. 1.

Fig. 5 is a detail vertical section taken on line 5—5 of Fig. 1.

Fig. 6 is a cross section taken on line 6—6 of Fig. 2.

2

Fig. 7 is an enlarged detail plan view of the pipe-engaging means shown in Fig. 1, in engagement with a drill pipe of relatively large diameter.

Fig. 8 is a view, similar to Fig. 7, with the pipe-engaging means in engagement with a drill pipe of relatively small diameter.

In this illustrative construction, as shown in the drawings, the improved spinning device, generally designated 1, is shown mounted on a supporting structure, generally designated 2. This supporting structure may assume various forms, but is herein desirably similar to that disclosed in my copending application Serial No. 506,131, filed of even date herewith. Evidently, the spinning device may be mounted in various conventional manners and when used on a conventional oil field drill rig it may be supported on vertical guideways and positioned either by springs or a fluid cylinder in such manner as to move the drill pipe engaged thereby axially in a vertical direction to bring the threads of the coupling pin of the upper pipe section into engagement with, or out of engagement from, the threaded socket of the adjacent lower pipe section. Such a vertically movable supporting structure may be similar to that disclosed in my copending application Serial No. 428,979, filed May 11, 1954, now matured into Patent No. 2,760,392, dated August 28, 1956. This vertically adjustable mounting for the spinning device also may be of the type known as a "stabbing device" which provides a spring effect to "jump" the pin out of the socket at the moment of disengagement of the joint, and the spring means allows the spinning device to move down with the pipe section gripped thereby to enable the connection of the threaded pin within the socket of the adjacent lower pipe section, all in a well-known manner.

35 In this instance, the supporting structure 2 comprises a vertical support or post 3 and the spinning device is mounted at its inner end on this vertical support to swing in horizontal planes. A hydraulic jack 4 is connected between an arm 5 secured to the vertical support or post 3 and to the frame or body of the spinning device for 40 swinging the latter horizontally and for holding the same in adjusted position.

The spinning device has a horizontal frame or body 6 provided with an inner tubular portion 7 secured to a turnable outer casing 8 on the vertical support or post 3. The frame or body 6 has an outer enlarged portion 9 provided with a centrally located horizontal guideway 10 extending radially with respect to the axis of the vertical support or post 3. The outer frame portion 9 is composed of upper and lower superimposed plate-like portions 11 and 12 and a connecting housing portion 13. Pivotally mounted on vertical pivot pins 14 spaced equidistantly from the axial center of the frame or body 6 are horizontally swingable arms or levers 15 which carry, at their outer portions, vertical shafts 16 which support anti-friction bearings 17 on which chain sprockets 18 are rotatably mounted. Guided for horizontal movement longitudinally of the frame or body 6 is a slide 19 on which a vertical shaft 20 is journaled in anti-friction bearings 21 and desirably formed integral with this shaft is a chain sprocket 22. Carried by the slide is a housing 23 in which the shaft 20 and its bearings are enclosed, and this housing desirably may contain a suitable lubricant for the moving parts contained therein. Mounted on the upper portion of the housing 23 on the slide 19 is a motor 24, herein desirably a conventional reversible motor of the hydraulic type, having its vertical power shaft 25 suitably coupled, at 26, to the upper portion of the shaft 20 of the drive sprocket 22. Passing around the sprockets 18 carried at the outer portions of the lever arms and about the drive sprocket 23 is an endless drive chain or belt 27, desirably of a relatively wide multiple construc-

60

65

70

tion (see Figs. 4 and 5). This drive chain extends transversely between the sprockets 18 (Fig. 3) which are idler sprockets and at its intermediate portion is adapted to embrace a drill pipe or drill collar designated 28 (Fig. 2). This endless chain desirably has numerous outer serrations or gripping teeth 30 so that when the intermediate outer portion of the drive chain is brought into embracing contact with, or wrapped partially about, the drill pipe or drill collar to be rotated, the pipe is firmly gripped. In the event an endless belt is employed in lieu of the chain, usual rollers or pulleys may be substituted for the three sprockets in an obvious manner.

In this improved construction, a pair of horizontal fluid jacks 31 are arranged longitudinally at the opposite sides of the body or frame 6 along the outer sides of the housing portion 13 (Fig. 3). These jacks comprise fluid cylinders 32 containing reciprocable pistons 33. The cylinders are pivotally mounted at their rearward ends on vertical pivot pins 34 secured within aligned openings in lateral ear-like portions 34' of the outer portion 9 of the frame or body 6. The pistons 33 have piston rods 35 projecting outwardly or forwardly from the cylinders and pivotally connected at 36 to the outer remote sides of the lever arms 15.

The lever arms 15 are desirably composed of upper and lower plates 37 held in spaced relation by upright blocks 38 (Fig. 4) and the lever plates and blocks are secured in rigid relation as by rivets 39 (see also Fig. 2). The piston rods 35 have integral with their outer portions eye-members or yokes 40 which carry vertical pivot pins or trunnions 41 on which the plates of the lever arms 15 are pivotally mounted above and below the drive chain 27. These eye-members 40 are cut away, at 42, so as to clear the drive chain when the lever arms 15 are retracted, as shown in Fig. 3, and when in retracted position these eye-members or yokes straddle the drive chain. Liquid under pressure may be delivered to the jack cylinders 32 through conduits 43 from any suitable source.

Also pivotally mounted on the pivot pins 14 above and below the plates 37 of the lever arms 15 are tong-like centering levers or arms 45 desirably composed of superimposed plates with the rearward portions of the plates of one lever interleaved with the plates of the other lever (Fig. 4). Levers 45 have curved outer or front end portions 46 which are engaged by the opposed reduced end portions 47 of the vertical shafts 16 on which the sprockets 18 are rotatably mounted. The inner portions of the levers 45 cross one another at the longitudinal median line of the frame or body 6 of the spinning device and, as shown in Figs. 7 and 8, the inner ends of the levers are loosely pivotally connected by vertical pivot pins 48 to slippers or pressure pads 49 which at their inner surfaces abut forwardly facing plane surfaces 50 of lateral lugs 51 integral with the slide 19 which carries the chain driving motor 24. Curved surfaces 52 on the arms engage the inner curved surfaces of the pressure pads 49 so that the pivot pins 48 take no part of the very heavy loads involved.

Threadedly secured at 53 to the housing 23 on the slide 19 is a horizontal rod 54 which extends longitudinally of the spinning device midway between the sides of the guideway 10. The inner end of this rod is threadedly secured at 55 to a circular plate 56 and interposed between this plate and an annular plate 57 secured to the housing portion 13 of the body or frame 6 are coil springs 58 and 59 arranged in concentric relation. These coil springs act on the outer plate 56 constantly to urge the slide 19 in an outward or rearward direction within its guideway 10.

The endless drive chain 27 may embrace drill pipe sections of different diameters and in Fig. 7 a relatively large size pipe or drill collar A is shown, and at this time the arms 15 are substantially in their innermost closed position with the slide 19 in substantially its outermost or rearmost position, with the springs 58, 59 compressed

as shown in Fig. 4. When a relatively small size drill pipe or drill collar, indicated at B in Fig. 8, is embraced by the drive chain the arms 15 swing inwardly toward one another and by the engagement of the shaft projections 47 with the curved outer ends of the centering levers 45 the latter, at their outer portions, are swung inwardly with the lever arms 15 thereby swinging the inner portions of the levers outwardly and through the slipper pads 49 engaging the lateral lugs 51 shoving the slide 19 outwardly or rearwardly along its guideway 10, forcing drive sprocket 22 back to the proper position, thus to maintain the endless drive chain under the proper gripping pressure. As the slide 19 moves rearwardly the springs 58, 59 expand while constantly urging the slide in its outward direction. Thus, either the relatively large size or relatively small size drill pipes, or intermediate sizes of drill pipe, may be embraced by the drive chain during the spinning operation while the pipe is at all times effectively gripped by the chain.

The general mode of operation of the improved spinning device will be clearly apparent from the description given: As stated above, the improved spinning device is adapted for association with a conventional make and break tong and may be operated to effect its spinning function when the threaded pin of the upper pipe section engaged thereby is brought into initial engagement with the threaded socket of the adjacent lower pipe section, in a manner well known to those skilled in the art. After the joint is broken, the spring or fluid elevated supporting structure 2, or so-called "stabbing device," by which the spinning device is carried causes the uncoupled section to "jump" suddenly upwardly, quickly to disconnect the joint, thus to reduce the possibility of thread damage, and during coupling of the joint the spinning device may move downwardly with the pipe section gripped thereby on its spring or fluid supporting structure.

The improved spinning device operates on substantially the same basic principle as my earlier device as disclosed in the above-mentioned copending application Serial No. 335,447. The spinning device is initially brought up against the drill pipe with the endless drive chain engaging and embracing the upper pipe section or drill collar and, as stated above, the improved spinning device may be mounted above the make and break tongs of my copending application Serial No. 428,979 referred to above. When the drive chain of the spinning device is brought up against the drill pipe, liquid under pressure may be supplied to the cylinders 32 of the fluid jacks to cause the pistons 33 to move inwardly or forwardly to swing the lever arms 15 inwardly toward one another about their pivots to bring the endless drive chain into firm gripping engagement with the drill pipe. Liquid under pressure may then be supplied to the hydraulic motor 24 to effect circulation of the endless drive chain rapidly to rotate the drill pipe section gripped thereby. The centering levers or arms 45 which are engaged by the reduced end portions of the shafts 16 on the lever arms 15 serve to center the spinning device with respect to the drill pipe and as the lever arms 15 swing inwardly with the reduced end portions of the shafts 16 in engagement with the centering levers 45, the slide 19 is shoved rearwardly along its guideway forcing the drive sprocket 22 back to the proper position. By the provision of the centering arms 45 cooperating with the slide 19 drill pipe sections or drill collars of different diameters may be firmly gripped by the endless drive chain while the spinning device is maintained centered with respect to the drill pipe. The spinning device may be readily released from the drill pipe simply by operating the fluid jacks to swing the lever arms 15 wide apart, as shown in Fig. 3, and thereafter the supporting structure 2 may be adjusted to swing the spinning device horizontally into an out-of-the-way lateral position, in the manner disclosed in my copending application Serial No. 506,131 mentioned above.

The spinning device may be operated to rotate the upper drill pipe section gripped thereby in either of opposite directions simply by reversing the driving motor 24 to enable the coupling of the drill pipe joint as well as the uncoupling thereof.

As a result of this invention, an improved drill pipe spinning device is provided for the pipe sections of a drill string such as used in oil well drilling, the spinning device engaging and firmly gripping the drill pipe in an improved and reliable manner. By the provision of the yieldable mounting for the chain drive sprocket, together with the associated centering arms, the drive chain may be maintained under the proper tension irrespective of the diameter of the drill pipe section gripped thereby. Also, the improved centering levers maintain the spinning device in proper centered position with respect to the drill pipe. The improved spinning device is not only simple and reliable in operation, but is also rugged in design, well adapted for its intended purpose. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. A spinning device for drill pipe comprising a frame, a pair of cooperating levers pivotally mounted on said frame and positioned to straddle a drill pipe, pipe-engaging and rotating means carried by said frame in association with said levers, means for swinging said levers inwardly toward one another to move said pipe-engaging and rotating means into pipe-engaging position, and cooperating means actuated by said levers for centering the device with respect to the drill pipe.

2. A spinning device as set forth in claim 1 wherein resilient means is provided for maintaining said pipe-engaging and rotating means in proper gripping engagement with the drill pipe, and said centering means is associated with said resilient means.

3. A spinning device as set forth in claim 1 wherein said centering means comprises a pair of cooperating lever arms pivotally mounted on said frame and positioned to straddle the drill pipe, said lever arms being actuated by said levers.

4. A spinning device as set forth in claim 2 wherein said centering means cooperates with said resilient means for permitting engagement of said pipe-engaging and rotating means with drill pipe of different diameters.

5. A spinning device for drill pipe comprising a frame having a longitudinal guideway, a pair of levers pivotally mounted on said frame in positions to straddle a drill pipe, an endless pipe-rotating member guided on said frame and cooperating with said levers, means for swinging said levers about their pivots to bring said endless rotating member into gripping engagement with the drill pipe, a slide guided for movement along said guideway, guide members carried by said slide and said levers for guiding said rotating member for circulation relative to said frame and said levers, resilient means cooperating with said slide for maintaining said endless member under proper tension when in pipe-engaging position, and centering arms pivotally mounted on said frame and actuated by said levers for centering the device with respect to the drill pipe.

6. A spinning device as set forth in claim 5 wherein said centering arms cooperate with said slide.

7. A spinning device as set forth in claim 6 wherein said slide has plane transverse abutment surfaces at the sides

thereof and said centering arms at their outer ends react against said abutment surfaces.

8. A spinning device as set forth in claim 7 wherein said pivoted centering arms carry pivoted pressure pads respectively engaging said abutment surfaces.

9. A spinning device as set forth in claim 5 wherein said centering arms cooperate with said resilient means for enabling said levers and said endless rotating member to cooperate with drill pipe of different diameters, said centering arms cooperating with said slide to move the latter along its guideway when pipe sections of different diameters are engaged by said endless rotating member.

10. A spinning device for drill pipe comprising a frame providing a longitudinal guideway, a slide guided for movement along said guideway, a motor driven member carried by said slide, a pair of levers pivotally mounted on said frame in positions to straddle the drill pipe, guides carried by said levers, an endless drive member driven by said motor driven member and guided by said guides on said levers, said endless drive member engageable with a drill pipe section for rotating the latter, spring means for urging said slide outwardly along its guideway for maintaining said endless drive member under proper tension, and a pair of centering arms pivotally mounted on said frame in positions to straddle the drill pipe, said centering arms being actuated by said levers for centering the device with respect to the drill pipe.

11. A spinning device as set forth in claim 10 wherein the pivots for a lever and arm of each pair are coaxial.

12. A spinning device as set forth in claim 10 wherein said centering arms react against said slide to move the latter outwardly along its guideway as said endless drive member is brought into engagement with drill pipe of different diameters.

13. A spinning device for drill pipe comprising pipe-gripping and rotating means, means for moving said pipe-gripping and rotating means into gripping relation with a drill pipe, and cooperating means actuated by said moving means upon movement of said gripping and rotating means into pipe-gripping position for centering the device with respect to the drill pipe.

14. A spinning device as set forth in claim 13 wherein said gripping and rotating means includes a member movable into pipe-engaging position, said moving means includes an element for moving said member, and said centering means includes a movable centering member actuated by said moving element.

15. A spinning device for a drill pipe comprising a frame, pipe-engaging and rotating means, means on said frame for moving said pipe-engaging and rotating means into and out of operative relation with the drill pipe to be rotated, and cooperating means actuated by said moving means for centering the device with respect to the drill pipe upon movement of said pipe engaging and rotating means towards operative relation with the drill pipe.

16. A spinning device as set forth in claim 15 wherein yieldable means is provided in association with said centering means for maintaining said pipe engaging and rotating means in proper gripping engagement with the drill pipe.

17. A spinning device as set forth in claim 16 wherein said yieldable means operates with said centering means for permitting engagement of said pipe engaging and rotating means with drill pipe of different diameters.

18. A spinning device for a drill pipe comprising a frame, a support member movably mounted on said frame, a motor driven member carried by said support member, actuating elements mounted on said frame for movement relative thereto, pipe-engaging and rotating means operatively associated with said actuating elements, means for moving said actuating elements to effect engagement of said pipe-engaging and rotating means with the drill pipe, yieldable means for urging said support

member in one direction in relation to said frame for maintaining said pipe-engaging and rotating means in proper relation with the drill pipe, and centering means movably mounted on said frame and operatively associated with said actuating elements for centering the device with respect to the drill pipe.

19. A spinning device as set forth in claim 16 wherein said yieldable means includes a yieldably mountable member and said moving means for said pipe-engaging and rotating means includes a moving element coating 10 with said yieldable mounting member.

20. A spinning device as set forth in claim 19 wherein

motor operated means is provided for driving said pipe engaging and rotating means including a motor driven element carried by said yieldably mounted member.
